(57) **CLAIM**

The ornamental design for a cylindrical tablet having separable mating components, as shown and described.

DESCRIPTION

FIG. 1 is a perspective view of a cylindrical tablet having separable mating components, according to my new design. FIG. 2 is a separated perspective view of my cylindrical tablet having separable mating components.

FIG. 3 is a side view of my cylindrical tablet having separable mating components.

FIG. 4 is a front view of my cylindrical tablet having separable mating components.

FIG. 5 is a back view of my cylindrical tablet having separable mating components.

FIG. 6 is a separated side view of my cylindrical tablet having separable mating components; and,

FIG. 7 is a perspective view of my cylindrical tablet having separable mating components, wherein the broken line showing multiple mating cylindrical tablets is included for the purpose of illustrating an environment and forms no part of the claimed design.

The dotted and/or broken lines depict environmental features, or the character or contour of the surfaces represented and are not a part of the claimed design.
